UNITED STATES PATENT OFFICE.

JOSEPH LOCKE, OF BALDWIN, PENNSYLVANIA, ASSIGNOR OF ONE-HALF TO
JOHN H. PHILLIPS, OF PITTSBURG, PENNSYLVANIA.

DESIGN FOR A PLATE OR PANE OF GLASS.

SPECIFICATION forming part of Design No. 31,762, dated October 31, 1899.

Application filed September 8, 1897. Serial No. 650,986. Term of patent 14 years.

To all whom it may concern:

Be it known that I, JOSEPH LOCKE, a citizen of the United States, residing at Baldwin township, in the county of Allegheny and State 5 of Pennsylvania, have invented a certain new and useful Design for Panes or Plates of Glass; and I do hereby declare the following to be a full, clear, and exact description of the invention, such as will enable others skilled in the 10 art to which it appertains to make and use the same.

This invention has relation to designs for plates or panes of glass.

The design constituting the subject-matter 15 of my invention is shown in the accompanying drawings, wherein—

Figure 1 is a perspective view of a plate or pane of glass made according to my design; Fig. 2, a sectional view of the same.

20 The leading features of my design consist, as shown in the drawings, of a plate A, rec-

tangular in outline, having a flat edge *a* and a raised central portion B, which on one side projects above the flat edge *a* and on the other side is depressed below the same. The outline 25 of the raised portion B coincides with the outline of the edge of the plate, and in cross-section the raised portion B is composed of the two angular surfaces C and D, the surface C being at a greater angle to the flat surface of 30 the edge *a* than the surface D and preferably slightly rounded, as shown.

Having described my design, I claim—

The design for a pane or plate of glass substantially as shown and described. 35

In testimony whereof I affix my signature in presence of two witnesses.

JOSEPH LOCKE.
